UNITED STATES PATENT OFFICE.

GEORGE WILLIAM MOHR, OF JERSEY CITY, NEW JERSEY.

FEED-WATER APPARATUS.

1,204,052.

Specification of Letters Patent.

Patented Nov. 7, 1916.

Application filed November 12, 1915. Serial No. 61,083.

To all whom it may concern:

Be it known that I, GEORGE W. MOHR, a citizen of the United States, and a resident of Jersey City, in the county of Hudson and State of New Jersey, have invented a new and Improved Feed-Water Apparatus, of which the following is a full, clear, and exact description.

The object of the invention is to provide 10 a new and improved feed water apparatus more especially designed for automatically and periodically feeding heated water under pressure into a boiler or other generator without any waste of the steam or other fluid 15 motive agent or the use of any lubricant.

In order to accomplish the desired result, use is made of a tank provided with a source 20 of water supply for charging the tank with water, a steam supply pipe connected with a steam compartment of a boiler or generator which is to be fed with heated water, a delivery pipe leading from the said tank for draining water therefrom into said boiler or generator, balanced twin valves within the 25 tank, of which one controls the said steam supply pipe and the other controls the said water delivery pipe, and a float controlled mechanism connected with the said twin valves for automatically and simultaneously 30 opening and closing the said twin valves.

A practical embodiment of the invention is represented in the accompanying drawings forming a part of this specification, in which similar characters of reference indicate corresponding parts in all the views.

Figure 1 is a side elevation of the feed water apparatus as applied, the tank being shown in section; Fig. 2 is an enlarged side elevation of the feed water apparatus with 40 the tank and parts of the valve mechanism shown in section; Fig. 3 is a sectional plan view of the same on the line 3—3 of Fig. 2; Fig. 4 is an enlarged cross section of the same on the line 4—4 of Fig. 2; Fig. 5 is a 45 similar view of the same on the line 5—5 of Fig. 3; and Fig. 6 is an enlarged face view of a portion of the strainer for straining the outflowing water.

A suitably constructed closed tank 10 is 50 supplied with water from a water supply pipe 13 connected with a water heater or other source of heated water supply and the tank 10 is supplied with steam from the steam compartment or dome of a boiler or other generator 16 by way of a steam supply pipe 18 and the accumulated water within

the tank 10 is allowed to flow periodically into the water compartment of the boiler 16 by way of a water delivery pipe 15, as hereinafter more fully explained. The pipes 13, 60 15 and 18 are provided with suitable strain-ers 17 and with valves 70, 71 and 67, respectively, and the pipe 13 is also provided with a check valve 14 intermediate the tank 10 and the valve 70 to prevent return flow of 65 the water from the tank in the pipe 13.

Within the tank 10 is arranged a float-controlled twin valve mechanism for automatically controlling the simultaneous in flow of the steam and the outflow of the 70 water, and this valve mechanism consists essentially of twin valves 20 and 22 having a common stem 21 slideable up and down in a valve body 23 provided at its upper and lower ends with valve seats 38 and 34 open- 75 ing in the same direction and adapted to be simultaneously opened and closed by the twin valves 20 and 22. The lower valve seat 34 connects with the water delivery pipe 15 and the upper valve seat 38 connects with 80 the steam supply pipe 18. The valve stem 21 is provided with a reduced portion 39 to provide a chamber 80 in the valve body 23 directly below the valve seat 38 to allow the steam to pass from the pipe 18 by way of 85 the valve seat 38 into the chamber at the time the valves 20 and 22 are open. The steam passes from this chamber 80 by way of a short upwardly extending pipe 19 into the 90 tank 10 near the top thereof.

The valve body 23 is provided with water outlets 36 immediately above the upper end of the lower valve seat 34 so that the water can flow from the tank 10 by way of the outlets 36 and the valve seat 34 to the water 95 delivery pipe 15 whenever the twin valves 20 and 22 are in open position. In order to prevent sediment or other extraneous matter from obstructing or impeding the movement of the valve 22, use is made of a sec- 100 tional strainer 35 surrounding the valve body 23 and extending over the outlets 36.

The twin valve 20, 22 is controlled in its opening and closing movement by a float controlled mechanism arranged as follows: 105 On the valve stem 21 are formed rack teeth 24 in mesh with a pinion 26 rotating on a short shaft 32 mounted in brackets 33 formed integrally with and projecting side- 110 wise from the valve body 23. The gear wheel 26 is in mesh with a segmental gear wheel 27 formed on the fulcrum end of a

float arm 28 provided at its free end with a float 29 of any approved construction. The float arm 28 is mounted to swing on a pivot 30 held on a standard 31 bolted or otherwise attached to the base plate 25 bolted or otherwise attached to a foundation 81 fastened by rivets or other means 82 to the bottom of the tank 10, as plainly indicated in Fig. 4. The float arm 28 is mounted 10 to swing up and down in a guide 48 bolted or otherwise fastened to the base plate 25.

In order to retain the float arm 28 in its extreme upper and lower position use is made of a retaining means arranged as follows, special reference being had to Figs. 3 and 5: The float arm 28 is held in uppermost position (see dotted lines in Fig. 5) by a latch 40 and is clamped in place when in lowermost position by a clamping lever 20 41, as shown in full lines in Fig. 5. The latch 40 is mounted to swing transversely on a pivot 42 held on the rear member of the guide 48. The upper end of the latch 40 is provided with a shoulder 47 for the 25 under side of the arm 28 to rest on, as indicated in dotted lines in Fig. 5, and the said latch 40 is also provided at its free end with a fork 46 into which projects a finger 45 formed on a dog 43 fulcrumed on a pin 44 held on the rear member of the guide 48. The forward movement of the latch 40 is limited by a stop 83 formed on the rear member of the guide 48, and the rearward movement of the latch 40 is limited by a 30 stop pin 84 attached to the said rear guide member.

The clamping lever 41, previously mentioned, is fulcrumed on a pivot pin 56 attached to the rear member of the guide 48, 40 and the said lever 41 is adapted to engage the rear face of the arm 28 to press the front face thereof against the front member of the guide 48 to securely clamp the arm 28 temporarily in position in the guide 48, 45 as illustrated in Fig. 5. The rear end of the lever 41 is pivotally connected by a link 55 with a trip lever 52 having its pivot 53 mounted in a bracket 54 forming part of the guide 48. The downward swinging 50 movement of the clamping lever 41 is limited by a stop pin 57 on the bracket 54.

In order to swing the latch 40 from under the arm 28 and to release the arm from the lever 41, the following releasing device is 55 provided: A float lever 49 is fulcrumed on a standard 50 bolted or otherwise attached to the base plate 25, and one end of the float lever 49 is provided with a float 51 of any approved construction, and the other end 60 of the said float lever 49 extends between the dog 43 and the forward end of the trip lever 52. The float 51 rises with the water accumulated in the tank 10 and when the water reaches a predetermined level then the 65 free end of the float lever 49 imparts a

swinging motion to the trip lever 52 whereby the clamping lever 41 is swung into the position shown in dotted lines in Fig. 5, thus releasing the float arm 28 to allow the float 29 to rise in the accumulated water. 70 The float arm 28 in its upward swinging movement engages the latch 40, which latter holds the arm 28 locked in uppermost position, as indicated in dotted lines in Fig. 5. When the water falls in the tank 10 the 75 float 51 sinks and in doing so its float lever 49 engages the dog 43 and swings the same upward thus causing the finger 45 to swing the latch 40 from under the arm 28 to release the latter and allow the same to swing 80 downward to lowermost position.

In order to counterbalance the arm 28 use is made of a counterbalancing lever 59 fulcrumed on a standard 60 rising from the base of the guide 48, and the right-hand end 85 of the lever 59 is provided with an adjustable weight 58 and its other end is provided with a pivoted latch 61 adapted to engage a shelf 63 attached to or formed on the arm 28. The downward swinging movement of the weighted end of the lever 59 is limited by a set screw 62 carried on the standard 60.

The tank 10 may be pre-heated and for this purpose use is made of a branch pipe 64 connecting the steam supply pipe 18 with the tank 10 and from the bottom of the latter leads a drain pipe 66 for carrying off the water of condensation from the tank 10. The pipes 64 and 66 are provided with suitable valves 68 and 69. An air cock 65 is attached to the top of the tank 10 to allow escape of air from the tank, as hereinafter more fully explained. When it is desired to pre-heat the tank 10 the valves 67, 70 and 71 are closed and the valve 68 and the air cock 100 105 65 are opened to allow steam to pass into the tank 10 to heat the same and drive out the air by way of the cock 65. When the tank is heated to the desired degree then the valve 68 and the cock 65 are closed and the 110 water of condensation in the tank 10 may now be drained out by opening the valve 69. The valve 69 is then closed. The tank 10 is preferably pre-heated, however, by hot water from the pipe 13 and for this purpose 115 the valves 67, 68, 69 and 71 are closed and the valve 70 and the cock 65 are opened to allow water to flow from the pipe 13 into the tank 10 and to allow escape of air from the tank by way of the cock 65. The valve 120 69 is next opened to drain out the water that is cold and when this has been done the valve 69 is closed to allow hot water to accumulate in the tank 10. The valves 67 and 71 are then opened and the air cock 65 is closed.

Presuming that the twin valves 20, 22 are closed and the float arm 28 is locked in lowermost position and the water accumulates in the tank 10, then the float 51 rises and when it reaches predetermined position its 130

float lever 49 engages the trip lever 52 and moves the clamping lever 41 out of engagement with the float arm 28 thus releasing the latter to allow the float 29 to rise. When 5 the float arm 28 swings upward it engages the latch 40 which latter holds the float arm in raised position. The upward movement of the float 29 causes opening of the twin valves 20 and 22 whereby the accumulated 10 water in the tank 10 can flow out of the same into the boiler 16 by way of the outlets 36, open valve seat 34 and pipe 15, and at the same time steam passes into the tank 10 by way of the pipe 18, open valve seat 38, compartment 80 and pipe 19. The float 51 falls with the outflow of the water in the tank 10 and when the float 51 moves into lowermost 15 position the arm 49 imparts a swinging motion to the dog 43 to swing the latch 40 out of engagement with the arm 28 thus allowing the latter to swing downward to lowermost position whereby the twin valves 20, 22 are returned to closed position on the seats 38 and 34 thereby stopping the outflow of 20 the water and the inflow of the steam from the tank 10. When the arm 28 moves into lowermost position as above described it is engaged by the clamping lever which locks the float arm 28 against upward movement. 25

30 During the downward swinging movement of the float arm 28 its shelf 63 engages the latch 61 so that the float arm 28 is counterbalanced and a swinging motion is given to the counterbalancing lever 59 and when the 35 float arm 28 moves nearly into lowermost position its shelf 63 glides over the latch 61 thus allowing return movement of the counterbalancing lever 59 and allowing the float 29 to move to lowermost locked position. 40 The above described operation is then repeated, that is, the water accumulating in the tank 10 causes the float 51 to rise, and when the float 51 reaches a predetermined position the arm 49 acts on the releasing lever 45 to cause the clamping lever 41 to release the arm 28. The latter now swings again upward to open the twin valves 20, 22 for the escape of the water from the tank and for steam to again pass into the tank. 50 It is understood that by this arrangement the twin valves 20, 22 are balanced as the upper end of the valve 20 is exposed to the pressure of the steam in the boiler 16 while the lower end of the valve 22 is exposed to 55 the pressure of the water within the boiler 16 and consequently the twin valve 20, 22 readily opens and closes and allows free flow of the water from the tank 10 into the boiler 16 whenever the twin valves 20, 22 are in 60 open position.

The tank 10 is preferably closed at one end and is provided with a removable cover 12 at the other end for the insertion of the valve mechanism above described. The 65 closed end of the tank 10 is preferably pro-

vided with a gage 11 to enable the operator to observe the rise and fall of the water within the tank.

Having thus described my invention, I claim as new and desire to secure by Letters Patent:

1. A feed water apparatus, comprising a tank, a steam supply pipe connected with the steam compartment in the boiler or generator which is to be fed with heated water, 75 a water supply pipe connected with a source of water supply and opening into the said tank, a water delivery pipe connected with the said boiler or generator, a valve mechanism having a valve casing connected at one end with the said steam supply pipe and at the other end with the water delivery pipe, the valve casing having connections at the upper and lower portions with the tank, and connected balanced twin valves 80 mounted in the said casing and automatically and simultaneously controlling the said steam supply pipe and the said water delivery pipe, and a float controlled mechanism within the said tank for controlling 85 the said twin valves.

2. A feed water apparatus, comprising a tank connected with a source of water supply for charging the tank with water, a steam supply pipe connected with the steam compartment in the boiler or generator which is to be fed with heated water for supplying the tank with steam, a water delivery pipe connected with the said boiler or generator, a valve mechanism having a 95 valve casing connected at one end with the said steam supply pipe and at the other end with the water delivery pipe, the valve casing having connections at the upper and lower portions with the tank, and connected balanced twin valves 100 mounted in the said casing and of which one controls the said steam supply pipe and the other controls the said water delivery pipe, and a float-controlled mechanism connected with the 105 said twin valves for automatically and simultaneously opening and closing the said twin valves.

3. A feed water apparatus, comprising a tank connected with a source of water supply for charging the tank with water, a steam supply pipe connected with the steam compartment in the boiler or generator which is to be fed with heated water for supplying the tank with steam, a water delivery pipe leading from the said tank for drawing the water therefrom into said boiler or generator, a valve casing within the said tank and having a steam inlet and a water outlet intermediate the ends of the casing, 115 the latter being connected at one end with the said steam supply pipe and at its other end with the said water delivery pipe, valve seats at the ends of the said casing and opening in the same direction, one of the 120

130

valve seats opening into the said steam supply pipe and the other valve seat opening into the said water delivery pipe, twin valves controlling the said valve seats, and 5 a float-controlled mechanism connected with the said twin valves for automatically and simultaneously moving the said valves into open or closed position on the said valve seats.

- 10 4. A feed water apparatus, comprising a tank connected with a source of water supply for charging the tank with water, a steam supply pipe connected with the steam compartment in the boiler or generator 15 which is to be fed with heated water for supplying the tank with steam, a water delivery pipe leading from the said tank for draining the water therefrom into said boiler or generator, a valve casing within 20 the said tank and having a steam inlet and a water outlet intermediate the ends of the valve casing, the latter being connected at one end with the said steam supply pipe and at its other end with the said water delivery pipe, valve seats at the ends of the 25 said casing and opening in the same direction, one of the valve seats opening into the said steam supply pipe and the other valve seat opening into the said water delivery pipe, twin valves controlling the said 30 valve seats, a strainer on the said valve body and extending over the said water outlet, and a float-controlled mechanism connected with the said twin valves for automatically 35 and simultaneously moving the said valves into open or closed position on the said valve seats.

5. A feed water apparatus, comprising a tank connected with a source of water supply for charging the tank with water, a steam supply pipe connected with the steam compartment in the boiler or generator 40 which is to be fed with heated water for supplying the tank with steam, a water delivery pipe connected with the said boiler or generator, a valve mechanism having a valve casing connected at one end with the said steam supply pipe and at the other end with the water delivery pipe, the valve casing 45 having connections at the upper and lower portions with the tank, and connected balanced twin valves mounted in the said casing and of which one controls the said steam supply pipe and the other controls the said water delivery pipe, a float controlled mechanism connected with the said twin valves for automatically and simultaneously opening 50 and closing the said twin valves, retaining means for retaining the said float controlled mechanism at the extremes of its operating positions, releasing means controlled by the water in the tank for releasing the said float controlled mechanism, and a counterbalancing means for the said float controlled mechanism.

- 60 6. A feed water apparatus, comprising a tank connected with a source of water supply for charging the tank with water, a steam supply pipe connected with the steam compartment in the boiler or generator 65 which is to be fed with heated water for supplying the tank with steam, a water delivery pipe connected with the said boiler or generator, a valve mechanism having a valve casing connected at one end with the said steam supply pipe and at the other end with the water delivery pipe, the valve casing having connections at the upper and lower portions with the tank, and connected balanced twin valves mounted in the said cas-

ply for charging the tank with water, a steam supply pipe connected with the steam compartment in the boiler or generator which is to be fed with heated water for supplying the tank with steam, a water delivery pipe connected with the said boiler or generator, a valve mechanism having a valve casing connected at one end with the said steam supply pipe and at the other end with the water delivery pipe, the valve casing 70 having connections at the upper and lower portions with the tank, and connected balanced twin valves mounted in the said casing and of which one controls the said steam supply pipe and the other controls the said water delivery pipe, a float actuated lever connected with the said twin valves for simultaneously opening and closing the same, retaining means adapted to engage the said float actuated lever, and a water float controlled member within the said tank for releasing the said retaining means.

7. A feed water apparatus, comprising a tank connected with a source of water supply for charging the tank with water, a steam supply pipe connected with the steam compartment in the boiler or generator which is to be fed with heated water for supplying the tank with steam, a water delivery pipe connected with the said boiler or generator, a valve mechanism having a valve casing connected at one end with the said steam supply pipe and at the other end with the water delivery pipe, the valve casing 80 having connections at the upper and lower portions with the tank, and connected balanced twin valves mounted in the said casing and of which one controls the said steam supply pipe and the other controls the said water delivery pipe, a float actuated lever connected with the said twin valves for simultaneously opening and closing the same, retaining means adapted to engage the said float actuated lever, and a water float controlled member within the said tank for releasing the said retaining means.

8. A feed water apparatus, comprising a tank connected with a source of water supply for charging the tank with water, a steam supply pipe connected with the steam compartment in the boiler or generator 90 which is to be fed with heated water for supplying the tank with steam, a water delivery pipe connected with the said boiler or generator, a valve mechanism having a valve casing connected at one end with the said steam supply pipe and at the other end with the water delivery pipe, the valve casing 95 having connections at the upper and lower portions with the tank, and connected balanced twin valves mounted in the said casing and of which one controls the said steam supply pipe and the other controls the said water delivery pipe, a float controlled mechanism connected with the said twin valves for automatically and simultaneously opening and closing the said twin valves, retaining means for retaining the said float controlled mechanism at the extremes of its operating positions, releasing means controlled by the water in the tank for releasing the said float controlled mechanism, and a counterbalancing means for the said float controlled mechanism.

110 9. A feed water apparatus, comprising a tank connected with a source of water supply for charging the tank with water, a steam supply pipe connected with the steam compartment in the boiler or generator 120 which is to be fed with heated water for supplying the tank with steam, a water delivery pipe connected with the said boiler or generator, a valve mechanism having a valve casing connected at one end with the said steam supply pipe and at the other end with the water delivery pipe, the valve casing 125 having connections at the upper and lower portions with the tank, and connected balanced twin valves mounted in the said cas-

130

- ing and of which one controls the said steam supply pipe and the other controls the said water delivery pipe, a float controlled mechanism connected with the said twin valves
- 3 for automatically and simultaneously opening and closing the said twin valves, retaining means for retaining the said float controlled mechanism at the extremes of its operating positions, releasing means controlled
- 10 by the water in the tank for releasing the said float controlled mechanism, a counter-

balancing lever within the said tank and provided at its free end with a pivoted latch, and means on the said float controlled mechanism engaged by the said latch.

15

In testimony whereof I have signed my name to this specification in the presence of two subscribing witnesses.
